UNITED STATES PATENT OFFICE.

CLIFFORD C. BRADBURY, OF GLENCOE, ILLINOIS.

VARIABLE-PITCH GEAR.

Application filed March 18, 1926. Serial No. 95,543.

My invention relates to variable pitch gears having particular application to the operation of a plurality of condensers in a radio receiving set.

6 The object of this invention is to provide ready means for changing the pitch of gears at localized positions on the gear wheels so that one or more gear wheels may be given non-uniform motion with respect to a third 10 wheel.

In tuned radio frequency receivers it is desirable that several tuning condensers be moved or rotated simultaneously under the influence of a single adjusting member. It 15 has been found difficult to manufacture condensers which originally have and retain exactly the same capacity for corresponding positions of rotor and stator. Furthermore, it is extremely difficult to construct the im- 20 pedencies which are connected parallel with the condensers so that the tuned circuits of several condensers and several impedencies will be tuned exactly alike for like settings of the condensers throughout the entire 25 range of positions of the rotors of the condensers with respect to the stators thereof.

My invention contemplates means for slightly adjusting the pitch of the operating gears of one or more of the condensers 30 so that all of the condenser rotors may be adjusted to the most accurately tuned positions at various frequencies by means which will bring the condenser parts to the same relative position whenever the parts are re- 35 turned to the position in which the setting has been made. The invention also contemplates means whereby the setting of the pitch for one position will have no effect upon the pitch at positions remote from 40 the position at which a setting is being made.

My invention also contemplates the use of a coiled spring as a gear whereby the coils of the spring may be slightly flexed either 45 toward or from one another as they enter the teeth of the meshing gear so that even if the pitch of the spring gear is not exactly the same as that of the meshing gear, the convolutions of the spring will nevertheless 50 enter between the teeth of the meshing gear, this structure obviating the necessity of a loose fit between the gears which would, of course, result in inaccuracy of relative positions between the two gears, depending upon 55 whether the driver was rotating in a clock-wise or a counter-clock-wise direction.

My invention is illustrated in the accompanying drawing in which:

Fig. 1 shows the general application of the invention to a condenser tuned radio frequency receiver.

Fig. 2 is a plan of two of the condenser units shown in Fig. 1.

Fig. 3 is a section through a gear wheel principle showing the construction of the 65 wheel.

Fig. 4 is an elevation of one of the gear adjusting mechanisms.

Fig. 5 is a section taken on the line 5—5 70 of Fig. 4.

Fig. 6 is an outline of the blank from which the gear supporting wheels are made up.

The gear carrying pulleys 10 may be formed of a pair of punchings 11 and 12 75 fastened together by means of eyelets 13 and suitably mounted upon a shaft 14. The punchings 11 and 12 are provided with a plurality of ears 16 and 17 between slots in which a plurality of screws 18 are mounted. These screws may be made from ordinary 80 wood screws and whether so constructed or otherwise contain threads of the same general shape and character as the threads of ordinary wood screws. These screws 18 are 85 positioned around the portions of the pulleys 10 through which it is desired to make changes in the gear adjustment. They may be continued through the entire circumference of the pulleys or through a part thereof 90 where changes are desired. A coil of spring wire 20 is wound about the pulleys 10, the ends of the spring being united as at 21, if complete rotation of the gear is not desired, or by any other suitable means, such as welding, brazing or soldering, if complete rotation 95 of the pulleys is desired.

The springs 20 are normally stretched or opened just sufficiently that the inner convolutions mesh with the threads on the 100 screws 18. The distance between convolutions at the outer part of the springs will, of course, be slightly greater than in the inner part where the springs engage the screws. By rotating one or more of the 105 screws by means of a screw driver the spring convolutions will be crowded in one direction or the other, depending upon the direction of adjustment of the screw to alter the relative position of the spring and pulley in 110 the region of the particular screw adjusted.

The idling gears 24 pivoted on studs 25

mesh with the main driving gear 26 which may be rotated by the hand wheel 27, thus driving the gears 10 which are rigidly secured to their respective shafts 14.

- 5 When this invention is applied to a radio receiving set having three condensers, the pulleys 10 are tightened upon the shafts 14 by means of nuts 28, or by other suitable means, at substantially the correct positions 10 for proper tuning on sending station, the frequency of which is such as to occupy a somewhat central position on the scale. After a crude adjustment has been made by slipping the shafts 14 within the hubs of the 15 wheels 10 and finally clamping the wheels 10 on their shafts 14 by means of a screw driver, the particular screws 18 which are positioned most nearly adjacent the idlers 24 are adjusted until the most accurate tuning is secured. The hand wheel 27 is then 20 rotated until other stations occupying positions remote from the central position of the dial can be heard and screw driver adjustments again made of the screws 18 which, 25 under these latter conditions, lie most nearly opposite the idler wheels 24. By making an accurate adjustment for as many positions 30 of the dial as there are screws 18 the receiving set will be accurately tuned at all of the exact positions at which adjustments 35 have been made. Ordinarily the amount by which the receiving set may be out of tune for positions lying between these adjustments are so small as to be negligible since the spring will assume an average pitch between screw adjustments if during the use 40 of the radio receiving set to which this invention is applied one or more of the condensers changes through atmospheric dampness or dryness. Corrections for these changes can be made by adjustment of the screws similar to the adjustments similarly made.

45 It is to be understood that this invention is susceptible of modifications without departing from the spirit or scope of the invention.

What I claim is:

- 50 1. A gear wheel or sector comprising grooved pulley, a coiled spring lying within the groove of said pulley, the convolutions of said spring forming the cogs of the gear wheel or sector and means for shifting a portion of the spring along the groove of 55 the pulley.

2. A variable pitch gear comprising a coil spring lying about a supporting member and movable therewith, together with means coacting with certain convolutions for shifting a portion of said spring on its support whereby the distance between convolutions is increased on one side of said means and decreased on the other side of said means.

3. A gear wheel or sector formed by stretching a coiled spring around a pulley-like supporting member and means engaging portions of the spring nearest the axis of the supporting member for preventing the spring from sliding around the supporting member and for varying the distance between certain of the convolutions.

4. A variable pitch gear comprising supporting member, thread screws rotatably mounted about the periphery of said supporting member, a coiled spring lying about the periphery of said supporting member and having its convolutions in registry with the threads of said screws, whereby said coiled spring may be shifted tangentially of said supporting member by the rotation of one or more of said screws.

5. A member adapted to be engaged by gear teeth comprising a coil spring provided with a plurality of convolutions, a support for said spring and means for moving some of the convolutions without affecting the remaining convolutions.

6. In combination, a driving means provided with gear teeth, a driven wheel provided with a spring rim adapted to act as gear teeth, and means for shifting a portion of the spring rim to vary the relative position of the driving means to the driven wheel.

7. In combination, a pair of inter-meshing gears, at least one of said gears being formed by the convolutions of a spring, and means for compressing or separating certain of said convolutions whereby the distance between convolutions is increased on one side of said means and decreased on the other side of said means, the spring being sufficiently flexible to adapt itself to the other gear whereby the convolutions may be slightly flexed either toward or from one another as they enter the teeth of the meshing gear.

In witness whereof, I hereunto subscribe my name this 16th day of March, 1926.

CLIFFORD C. BRADBURY.
